US00D517552S

(12) **United States Design Patent** (10) Patent No.: **US D517,552 S**
 Sakamoto et al. (45) Date of Patent: **** Mar. 21, 2006**

(54) **KEYBOARD**

(75) Inventors: **Toru Sakamoto**, Tokyo (JP); **Yoshiya Watanabe**, Tokyo (JP); **Yasuhisa Kaneda**, Tokyo (JP); **Kanae Fukamatsu**, Tokyo (JP); **Michio Deguchi**, Tokyo (JP)

(73) Assignee: **Sony Computer Entertainment Inc.**, Tokyo (JP)

(**) Term: **14 Years**

(21) Appl. No.: **29/216,870**

(22) Filed: **Nov. 10, 2004**

(30) **Foreign Application Priority Data**

May 10, 2004 (JP) D2004-013735

(51) LOC (8) Cl. **14-02**

(52) U.S. Cl. **D14/390**

(58) Field of Classification Search ..... D14/455, D14/392, 320, 388, 356, 390, 391, 394, 396, D14/399, 400, 401, 432; 200/6 R, 7, 5 A; 235/145 R, 146, 145 A; 341/22, 23; 345/168, 345/169, 156; 400/485, 82, 88, 700, 472, 400/556.1-556.2; 455/554.2, 557, 560, 73, 455/74, 74.1; 248/309.1, 300; 713/300; 463/1, 463/47, 37, 48, 40-43; D18/2, 7, 12.2; 178/17 A, 178/17 C, 18.03; 361/680; 379/433.07, 447, 379/455

(57) **CLAIM**

The ornamental design for a keyboard, as shown and described.

DESCRIPTION

FIG. 1 is a front elevational view of a keyboard showing our new design;

FIG. 2 is a rear elevational view thereof;

FIG. 3 is a left side elevational view thereof, a right side elevational view thereof being a mirror image;

FIG. 4 is a top plan view thereof;

FIG. 5 is a bottom plan view thereof;

FIG. 6 is a front top right perspective view thereof;

FIG. 7 is a rear bottom left perspective view thereof; and,

FIG. 8 is a reduced front elevational view thereof, showing a using condition.

The broken line showing of the environment are for illustrative purposes only and forms no part of the claimed described.

1 Claim, 4 Drawing Sheets
